Inventor:

James L. McClintock,

By Langdon Moore, Attorney

UNITED STATES PATENT OFFICE.

JAMES L. MCCLINTOCK, OF WICHITA, KANSAS, ASSIGNOR OF ONE-THIRD TO R. C. WELLMAN AND ONE-THIRD TO W. H. MCCOIN, BOTH OF WICHITA, KANSAS.

ANTIRATTLING DEVICE.

Application filed April 14, 1922. Serial No. 552,687.

To all whom it may concern:

Be it known that I, JAMES L. MCCLINTOCK, a citizen of the United States, residing at Wichita, Kansas, have invented certain new and useful Improvements in an Antirattling Device, of which the following is a specification, reference being had thereto to the accompanying drawing.

This invention comprises an anti-rattling device. It is a continuation of and improvement on the structure set forth in my co-pending application Serial No. 248,325. It is contemplated, in addition to the objects and advantages therein enumerated, to provide a device having a base or support made of a piece of material which may be used on either side, or turned upside down as occasion may demand, the associated parts being interchangeable and reversible to accord with the location and position of the plate.

Another object is to reduce the number of working parts and simplify their assemblage. Further advantages will be apparent from the description which follows.

25 A drawing illustrating an embodiment of the invention accompanies the specification, the following views being shown:

Fig. 1, is a fragmentary view in side elevation certain parts being removed and showing the position of the device when in operative position;

Fig. 2, is a view in vertical section through a window to which the device has been attached;

35 Fig. 3, is a view in perspective of the device itself.

In these drawings 1 designates a plate, base, or body portion which constitutes a support for the other working parts of the 40 device when assembled. It is provided with openings 2 for the reception of means for securing it in place in any desired location, such means being here shown as screws, 3.

Associated with this plate there is a spring 45 pressed and resiliently mounted roller 4. It is mounted so as to normally extend outwardly beyond the edge of the plate as shown in Fig. 3, but when in use is forced back into the position shown in Fig. 1. This 50 roller is carried on a bent portion 5 disposed on an offset portion 6 of a resilient arm 7. The offset portion of the arm acts as a housing or confining means for the roller and the arm 7, of which it is a continuation is normally in sliding engagement with a face of

the plate when secured thereto. For this purpose the arm 7 is provided with a looped portion 8 adapted to bear upon and encircle one of the screws 3, acting as a bearing and means for holding the arm and roller in position on the plate. 60

Means are provided for pressing the roller outwardly with a resilient tension, and for varying the degree of this force as occasion may require. As here shown, the looped portion 8 of the arm 7, is provided with an extension constituting another arm 9, in spaced relation to arm 7 and at an angle thereto. This arm has, at its free end, a bent or angulated portion 10 adapted to be 70 disposed in any one of a series of holes 11 disposed in the plate 1 and adapted to increase the tension on arm 7, depending upon which one of the holes the bent portion 10 occupies. The arms being made of resilient 75 material, the tension may be readily adjusted to accommodate a large variety of uses.

In Fig. 2, the device is shown applied to a window 12, by cutting out a portion of the 80 frame so as to allow the roller to extend out beyond the plane of one surface. The plate 1 is attached to the window by screws 3, one of which passes through the looped portion 8 of the arms. The tendency of the roller 85 to extend outwardly under pressure of the arms is resisted by a portion 13 of the window frame which forms the slideway for the window and this exerts a pressure against the window itself which keeps it tightly in 90 engagement with another portion 14 of the slideway. This not only prevents rattling, but insures air and dust tight engagement between the parts, and dispenses with the use of window weights. The tension is sufficient to allow the window to be moved 95 readily, but also to hold it in any desired position. The plate being absolutely flat and unbroken, permits it to be used on either side and the looped portion bearing on one of the screws, allows the roller to be used interchangeably on either end of the plate or either side thereof. The entire device is out of sight when attached and consequently not subject to interference or injury. 100

While the present embodiment constitutes a very simple and efficacious means of accomplishing the objects to be attained, it will be understood that I do not wish to limit myself to the precise form of this dis- 110

closure, as many changes in the general construction and arrangement of the parts, are contemplated as within the scope of the invention as set forth in the claims.

5. What I claim is:

1. An anti-rattling device comprising a base provided with an opening through which a fastening means is adapted to pass to secure the base in position; a spring member having a portion adapted to cooperate with the fastening means, to connect the spring with the base; a frame engaging arm extending from the spring member; and a tension arm connected with the spring member, the base being provided with a plurality of openings into which a portion of the tension arm is adapted to take, to vary pressure of the frame engaging arm on the frame.

2. An anti-rattling device comprising a base provided with an opening through which a fastening means is adapted to pass to secure the base in position; a spring member having a portion adapted to cooperate with the fastening means, to connect the spring with the base; a frame engaging arm extending from the spring member; a tension arm connected with the spring member, the base being provided with a plurality of openings into which a portion of the tension arm is adapted to take, to vary pressure of the frame engaging arm on the frame; and a roller on the frame engaging arm.

3. An anti-rattling device including a base provided with an opening for the reception of means for securing it in place; a spring member having a portion formed to cooperate with the securing means to hold the spring in place; an arm on the spring member adapted to be secured to the base to vary the tension of the spring member, said base being provided with openings in spaced relation; and the arm having a portion adapted to be placed in certain of the openings.

4. An anti-rattling device comprising a base provided with an opening through which a fastening means is adapted to pass to secure the base in position; a spring member having a portion adapted to cooperate with the fastening means, to connect the spring with the base; a frame engaging arm extending from the spring member; and a tension arm connected with the spring

member, the base being provided with a plurality of openings into which a portion of the tension arm is adapted to take, to vary pressure of the frame engaging arm on the frame, said openings into which a portion of the tension arm is adapted to take, being placed in definite relation to the opening through which the fastening means is adapted to pass, whereby the base may be turned over and the parts assembled in similar arrangement on the opposite side of the base.

5. An anti-rattling device comprising a base provided with openings at opposite ends thereof for the reception of a fastening means for securing the base in place; a spring member having a portion adapted to cooperate with a portion of the fastening means, to connect the spring with the base; a frame-engaging arm extending from the spring member, and a tension arm extending from the spring member; said base being provided with an opening disposed between the openings for the reception of the base attaching means, and into which a portion of the tension arm is adapted to take, whereby the base may be reversed and inverted, and the parts assembled in similar arrangement on either side of the base.

6. An anti-rattling device comprising a base provided with openings at opposite ends thereof for the reception of a fastening means for securing the base in place; a spring member having a portion adapted to cooperate with a portion of the fastening means, to connect the spring with the base; a frame-engaging arm extending from the spring member; and a tension arm extending from the spring member; said base being provided with a plurality of openings disposed in predetermined relation to the openings for the reception of the base attaching means, and into which a portion of the tension arm is adapted to take to vary pressure of the frame engaging arm on the frame, whereby the base may be reversed and inverted, and the parts assembled in similar arrangement on either side of the base.

In testimony whereof I hereto affix my signature.

JAMES L. McCLINTOCK.
